COLCHICINE GLYCOSYRRETINATE

Alfred Halpern, Great Neck, N.Y., assignor to Synergistics, Inc., New York, N.Y., a corporation of New York

Filed Feb. 21, 1958, Ser. No. 716,658
3 Claims. (Cl. 260—559)

The present invention relates to a new therapeutic compound, colchicine glycyrrhetic acid, the method of preparing the same, and dosage forms incorporating the compound.

Colchicine has been widely employed both to diagnose and treat gout and gouty arthritis, and particularly the acute attack thereof. Unfortunately, the administration of this agent often causes severe gastric distress resulting from the local irritation of the colchicine and its derivatives. The degree of local gastro-intestinal distress is proportional to the amounts of the drug ingested. It is well known that colchicine undergoes hydrolytic decomposition to form essentially inactive therapeutic compounds which, nevertheless, contribute to the noxious local effects. When a portion of a dose of colchicine is hydrolyzed, to an inactive form, a greater dosage is required to produce the desired therapeutic effect and consequently a higher index of local irritation results. In some instances, this ratio of local irritation to quantity of drug ingested is such as to preclude the use of the drug for these patients. By combining the very large molecule, glycyrrhetic acid, with the large colchicine molecule, an insoluble derivative results which is far less irritating than the smaller mobile molecule. When colchicine glycyrrhetinate is subjected to a hydrolyzing medium of either water or dilute acid, less than one percent of the molecule is destroyed, whereas the hydrolytic destructive rate is increased by ten to fifty times when the smaller colchicine molecule is treated in a similar manner. Furthermore, if the pH of the media is maintained to at least pH 3, virtually no destruction results and the full therapeutic effect of a given dose is achieved.

It is an object of the present invention to provide a more sensitive control of therapy of the patient and to provide the means to minimize the incidence of gastrointestinal distress resulting from local irritation. Further, colchicine-glycyrrhetinate makes available the colchicine moiety to patients who have previously been denied its beneficial effects because of an extreme sensitivity to the local irritation of colchicine and/or colchiceine.

It is a still further object of the present invention to provide means to simultaneously adduce the steroid potentiating properties of the glycyrrhetic acid moiety to enhance the effectiveness of the colchicine moiety.

Colchicine, an alkaloid obtained from plants of various species of genus *Colchicum*, usually *Colchicum autumnale* Linne, and commonly called yellow saffron, has been used for centuries in the specific treatment of gout.

It appears that the structural formula of colchicine is as follows:

2

Colchicine is an odorless alkaloidal base occurring as pale yellow amorphous scales or powder which darkens on exposure to light. One gram of colchicine is soluble in 25 ml. of water and in about 220 ml. of ether. It is freely soluble in alcohol and in chloroform. Its melting point is between 153 and 157° C. Colchicine is readily decomposed by dilute acids to produce methyl alcohol and the demethylated derivative, colchicine, which is virtually without therapeutic activity.

10 The acid hydrolytic decomposition of colchicine may be postulated as follows:

Colchicine has been shown to possess only a fraction of the biological activity of colchicine. Thus, the activity of orally administered colchicine is at least partially lost by the action of the acid medium of the gastric contents, although the local irritation to the gastrointestinal tract is not altered by the demethylative decomposition.

35 Through the proper control of the pH of the gastric fluid, an inhibition of the acidic decomposition results. While pH buffering results in good order of protection, optimal activity is achieved when the buffer is also capable of exerting an absorptive action, thereby minimizing the 40 number of free molecules in solution. Aluminum hydroxide is a preferred absorbent-protective buffer for these reasons and also because it exerts a demulcent action to the gastric mucosa.

The manifestations of gastrointestinal toxic reactions are often taken as an index that the level of tolerance for the drug has been reached. This is based upon the supposition that the gastrointestinal toxicity is solely due to central nervous system origin. However, the fact that larger doses may be administered intravenously indicates that at least a portion of the gastrointestinal distress following oral administration must be due to local irritation in the stomach. The presence of an agent such as aluminum hydroxide gel, both through its antacid effect in retarding hydrolysis of the colchicine and through its demulcent protection of the gastric mucosa minimizes the possibility of local gastric irritation and consequently reduces the possibility of a false index of therapeutic limit.

Although colchicine has been called the "sovereign remedy for gout" and its specificity is such that a therapeutic trial with colchicine is frequently used to establish the diagnosis of gout, neither the pharmacodynamics of colchicine nor the pathogenesis of gout, have been completely established. Since gout is related to abnormal uric acid metabolism, it has been assumed that colchicine in some way affects the uric acid metabolism.

Recent data suggest that colchicine may act as a stressing agent causing a release of adrenal corticosteroids. Furthermore, numerous investigations have demonstrated the fact that there is a pituitary-adrenal defect in gouty persons manifested by adrenocortical hormone deficiency.

Glycyrrhetic acid (also known as glycyrrhetic acid) is a polyterpene with the following structural formula:

Glycyrrhetic acid is obtained by acid or alkaline hydrolysis of glycyrrhizic acid which is extracted from the dried rhizome and roots of several varieties of *Glycyrrhiza glabra* and occasionally from other species of *Glycyrrhiza*. It has been found that two or more stereoisomers occur in the hydrolysate of the glycoside, glycyrrhizic acid. The melting point range for glycyrrhetic acid has been reported as 270-298° C. This substance has been found to be soluble in alcohol, dioxane and chloroform, and practically insoluble in petroleum ether and water.

Considerable clinical data indicates that glycyrrhetic acid is capable of exhibiting desoxycortico-steroid-like activity and of potentiating amounts of the corticosteroids which by themselves are inadequate to meet physiologic needs. Thus, glycyrrhetic acid is useful not in direct substitution for corticosteroids, but for enhancement of the activity of circulating endogenous adrenocortical hormones.

Colchicine glycyrrhetinate is prepared through the interaction of equimolecular portions of colchicine and glycyrrhetic acid in anhydrous soluton at moderately elevated temperatures. It is essential that the reaction takes place in anhydrous medium or hydrolytic cleavage of the complex salt will occur. The lack of appreciation of the need for reaction in an anhydrous medium has previously led to the inaccurate opinion that colchicine is not basic and hence does not combine with acids to form salts. Purification may be achieved by recrystallization.

The compound, colchicine glycyrrhetinate, is obtained as a pale yellow crystalline powder with extremely bitter taste and a faint odor of licorice. It melts with decomposition at 185-190° C. In ethanol, the U.V. absorption spectrum of the compound shows a peak absorption at 245 mu. See FIG. 1 which shows such a spectrum of a solution of 1 mg. of the compound per 100 ml. of 95% ethanol. At 25° C., it is less than 0.25% soluble in water; approximately 1% soluble in alcohol, 5% soluble in ether, less than 1% soluble in acetone and less than 0.2% soluble in petroleum ether.

The empirical formula of colchicine glycyrrhetinate is C₅₂H₇₁NO₁₀. Elemental analysis of this compound shows the following percentage composition: carbon 71.78, hydrogen 8.24, oxygen 18.39, nitrogen 1.71. The molecular weight of colchicine glycyrrhetinate is 870.1, the percentage composition of which is: colchicine moiety 45.90 percent, and glycyrrhetic acid moiety 54.10 percent.

Its structural formula may be postulated as follows:

Colchicine glycyrrhetinate is a new therapeutic agent, useful in relieving the symptoms of acute gouty arthralgia, in reducing the frequency of occurrence of acute attacks, and in preventing or modifying impending attacks.

In treatment of the acute attack, 1.00 mg. of colchicine glycyrrhetinate is administered every 1/2 to 1 hour until relief is obtained or gastrointestinal distress is manifested.

A typical pattern of symptoms usually precedes an acute attack for each person afflicted with gout. As this pattern becomes known to the individual, he is able to recognize the prodromal symptoms of an impending attack. The prompt ingestion of from 1.00 to 2.25 mgm. of colchicine glycyrrhetinate every two hours for a total of 3 or 5 doses will usually abort the attack.

The frequency of occurrence of acute attacks may be reduced by the ingestion of 1.00 to 2.25 mgm. of colchicine glycyrrhetinate once or twice a week or every other night before retiring, or even as frequently as every night, depending upon the particular patient's needs.

The usefulness of colchicine glycyrrhetinate is further extended by its adsorption onto the antacid, buffering adsorptive agent aluminum hydroxide gel.

The inclusion of the antacid buffering adsorptive agent serves to maintain the integrity of the colchicine moiety of this compound until absorption has occurred. By suppressing the acid hydrolysis of colchicine to the practically therapeutically inert colchicine, the antacid adsorptive agent assures maximum therapeutic utilization of the administered dose.

The following examples illustrate the method of preparation of the products of this invention:

Example 1

To 400 cc. of anhydrous isopropanol is added 0.05 mole glycyrrhetic acid and 0.05 mole of colchicine with thorough mixing. The solution is refluxed with heating for about 1/2 hour, then evaporated under reduced pressure to syrupy consistency. The material is redissolved in 100 cc. of anhydrous isopropanol and recrystallized by precipitation with anhydrous ether. The crystalline compound obtained exhibits the following properties: a pale yellow color with an extremely bitter taste and faint odor. It melts (with decomposition) at 185-190° C. A sharp absorption band at 245 millimicrons wavelength is exhibited by this compound in ultraviolet analysis in ethanol. At 25° it is less than 0.25% soluble in water, approximately 1% soluble in alcohol, 5% soluble in ether, less than 1% soluble in acetone and less than 0.2% soluble in petroleum ether.

Example 2

In place of the isopropanol described in Example 1 may be substituted wholly or in part, any anhydrous alcohol of the class ROH, wherein R represents a straight or branched-chain alkyl group containing up to five atoms of carbon.

5

Example 3

Another method of preparing colchicine glycyrrhetinate is to proceed as in Example 1 or in Example 2, substituting in either instance petroleum benzin for the anhydrous ether used in the recrystallization procedure.

Example 4

For each part of the compound obtained in Examples 1, 2 and 3, is added 100 parts of dried aluminum hydroxide gel. The mixture is moistened with a 50 percent alcohol-water solution, using sufficient solution to form a slurry. The slurry is stirred for twenty minutes at room temperature and then air dried to result in an adsorbed colchicine-glycyrrhetinate-gel complex.

Example 5

The product of Example 4 may be filled into capsules each of which contains 1.0 mg. of colchicine-glycyrrhetinate and 100 mg. of aluminum hydroxide gel.

Example 6

To the product of Example 4 is added the conventional excipients necessary for tablet preparation and then compressed into tablets, the weight of which is adjusted, so that each tablet contains 1.00 milligram of colchicine 25 glycyrrhetinate and 100 milligrams of aluminum hydroxide gel.

6

It is not desired to be limited except as set forth in the following claims, the above description being by way of illustration of the invention.

What is claimed is:

- 5 1. Colchicine glycyrrhetinate.
- 2. The method of preparing colchicine glycyrrhetinate which comprises dissolving colchicine and glycyrrhetic acid in an anhydrous alkanol selected from the group consisting of those alkanols having from 1 through 5 10 carbon atoms, and recovering colchicine glycyrrhetinate therefrom.
- 3. The method of claim 2 and the step of purification of the resulting glycyrrhetinate by means of sequential redissolving in said anhydrous alkanol and crystallization 15 therefrom by an anhydrous crystallizing agent selected from the group consisting of anhydrous ether and petroleum benzin.
